UNITED STATES PATENT OFFICE.

GUSTAVE STROHAKER, OF WALLINGFORD, CONNECTICUT, ASSIGNOR TO
INTERNATIONAL SILVER CO., OF MERIDEN, CONNECTICUT, A CORPO-
RATION OF NEW JERSEY.

DESIGN FOR A HANDLE FOR A SPOON, FORK, OR SIMILAR ARTICLE.

No. 38,232.

Specification for Design.

Patented Sept. 11, 1906.

Application filed July 28, 1906. Serial No. 328,273. Term of patent 7 years.

To all whom it may concern:

Be it known that I, GUSTAVE STROHAKER, a citizen of the United States, residing at Wallingford, in the county of New Haven and State of Connecticut, have invented a new, original, and ornamental Design for a Handle for a Spoon, Fork, or Similar Article; and I do hereby declare the accompanying drawing to be a full, clear, and exact illustration of the same and represents a face

view of a handle for a spoon, fork, or similar article embodying my design.

I claim—

The ornamental design for a handle for a spoon, fork or similar article as shown.

GUSTAVE STROHAKER.
